UNITED STATES PATENT OFFICE.

WALTER B. PAYNE, OF ROCHESTER, NEW YORK, ASSIGNOR TO THE TODD COMPANY,
INC., OF ROCHESTER, NEW YORK, A CORPORATION OF NEW YORK.

PRINTING MACHINE.

Application filed November 12, 1923. Serial No 674,207.

To all whom it may concern:

Be it known that I, WALTER B. PAYNE, a citizen of the United States, residing at Rochester, in the county of Monroe and State of New York, have invented certain new and useful Improvements in Printing Machines; and I do hereby declare the following to be a full, clear, and exact description of the same, reference being had to the accompanying drawings, forming a part of this specification, and to the reference numerals marked thereon.

This invention relates to printing machines of the variety, for example, adapted for printing legends, such as monetary values, on checks, drafts and similar work and comprising a plurality of type forms and a platen having a relative movement effected by manual means for bringing the platen and the forms selectively and successively to position for printing cooperation, one object of the invention being to provide an improved machine of this character having stop means adapted to be set for arresting the selective movement of the parts in a quick and positive manner with a predetermined one of the latter accurately positioned in printing relation. More specifically stated, it is an object of the present invention to provide a machine of this character having a platen and a carrier shiftable by manual means in cooperation with an index or dial to bring the type forms selectively to position for cooperation with the platen, together with auxiliary key operated stop means adapted to be set for positively stopping the selective movement of the manual means in positions corresponding to selected type forms and thereby increasing the speed and accuracy of operation.

To these and other ends the invention resides in certain improvements and combinations of parts all as will be hereinafter more fully described, the novel features being pointed out in the claims at the end of the specification.

In the drawings:

Fig. 1 is a top plan view of a machine embodying the present invention.

Fig. 2 is an enlarged longitudinal sectional elevation of the same partly broken away;

Fig. 3 is a transverse sectional elevation substantially on the line 3^a—3^a in Fig. 2;

Figs. 4 and 5 are transverse sectional ele-

vations substantially on the line 4^a—4^a in Fig. 2 and showing the parts in different positions;

Fig. 6 is a fragmentary sectional view on the line 6^a—6^a in Fig. 2;

Fig. 7 is a top plan view with portions of the casing removed to illustrate interior parts;

Fig. 8 is a similar view but showing parts in a different position and

Figs. 9 and 10 are enlarged sectional elevations substantially on the line 9^a—9^a in Fig. 2 showing a trip device.

Similar reference numerals throughout the several views indicate the same parts.

The invention is embodied in the present instance in a motor driven machine such as fully shown and described in my copending application for Letters Patent, Ser. No. 563,153 filed May 23, 1922, for printing apparatus so that but a brief description of the same sufficient for an understanding of the present invention appears to be necessary.

This machine comprises, generally speaking, a frame having a base 15 and an upper casing 16 resting thereon and hinged thereto at one side, as at 17, with a slot 18 therebetween at one side of which the work is inserted on a printing bed 19 formed by the top of the base. Rotatably supported in the latter and projecting through a slot in the printing bed is a platen wheel 19^a, Fig. 4 for pressing the work from below against a plurality of type forms 20 on a carrier 21, of generally cylindrical form, splined on a main shaft 22 rotatably supported at its ends in the casing 16. The type forms extend circumferentially of the carrier in longitudinally spaced arrangement so that they may be brought individually and successively into printing relation with the platen by a selective sliding movement of the carrier along its shaft, as well understood in the art.

Manual means are provided for effecting the relative selective movement of the platen and type forms comprising preferably a yoke 23, Figure 2, having spaced arms 24 embracing the ends of the carrier and rotatably and slidably engaging the main shaft. Mounted on the yoke are suitable inking rolls 25 for the type. The yoke is shifted longitudinally to select the type by means comprising an arm 26, Fig. 4 fixed on the yoke and extending throughout a slot in the top of the casing at which end it carries

2
a handle 27. The latter is provided with a pointer 28 movable with the handle over a dial 29 on the casing marked with the type forms on the carrier, to provide an indexing device by means of which any type form may be selected and manually moved to printing position preparatory to a successive rotation of the carrier effected by intermittent connection of its shaft with a motor 30 mounted on the casing, it being apparent that as the carrier is rotated the selected type form is impressed upon the work by a rolling printing and feeding cooperation with the platen. The forms are thus successively selected and printed individually by alternating selecting and printing operations until a desired legend is complete.

20 The printing movement of the carrier is accomplished as stated by intermittently connecting the same with a continuously running motor 30 mounted on the casing and connected by a gearing, as shown in Figs. 2 and 3, with the main shaft through a gear 31 fixed on a sleeve 32 rotating on the shaft and connected therewith by a mechanism which will now be described.

25 The yoke 23 for shifting the type carrier has in addition to its longitudinal selective movement a rocking movement through a small angle about the main shaft imparted by depressing the handle 27 after the selection of each type form. The yoke carries an abutment 33, Fig. 6 brought by such rocking movement into contact with a bail 34 fixed on a shaft 35 mounted for rocking movement in the casing and projecting through one end thereof into the compartment 36 in which the gearing connection with the motor is located. Fixed on this end of the shaft is an arm 37, Fig. 10 having pivotally mounted thereon a lever 38, one arm of which is shouldered for engagement with an arm of a lever 39 pivotally supported on the casing. The other arm of lever 39 is arranged to normally engage one end of a dog 40 pivotally supported on a disc 41 fixed on the main shaft. A spring 42 tends to move the dog to bring a lug 43 thereof into engagement with one of the teeth 44 formed on the hub of the gear 31 continuously rotated by the motor through the gearing connection described. As shaft 35 is rocked by handle 27 the lever 38 is moved to swing the lever 39, as shown in Fig. 9, 30 to release dog 40 which immediately locks the disc and main shaft to the motor driven sleeve 32, so that the carrier is set in rotation. As the dog 40 rotates past the lever 38, however, a portion thereof engages the other arm of lever 38 and swings the latter so as to trip lever 39 which thereupon returns under the action of its spring to the position shown in Fig. 10 to engage and swing dog 40 clear of tooth member 44 as the dog 35 is rotated back to initial position. A pawl

45 cooperating with a shoulder on disc 41, holds the shaft and carrier against reverse rotation. At the end of each complete revolution of the type carrier therefore the latter is automatically disconnected from the driving means and brought to rest preliminary to a successive selecting movement.

50 While the type forms may be selected for printing as already described, by manually adjusting handle 27 and its pointer 28 into registry with the corresponding indicia on the dial, it has been found that this result may be accomplished more rapidly and accurately by the use of a stop mechanism adapted to be set to provide a positive stop for the selectively movable parts corresponding to one or more of the different type forms as may be found desirable. This is carried out by providing stop shoulders 55 adapted to be positioned in the path of movement of the type carrier yoke and against which the latter is moved by handle 27 to quickly and accurately position the latter with a desired type form in printing relation. In the present instance the casing 50 of the machine is equipped with a sheet metal housing comprising a top plate 46, Figs. 4 and 5, supported at one side on the casing, and secured thereto, as by means of screws 47, Fig. 7. The plate is secured at 55 its opposite side to an outer housing wall 48 the lower side of which is fixed to the casing as at 49. An angular bottom plate 50 is secured as shown to the outer wall 48 and to the top plate in spaced relation with the latter. Sliding longitudinally in slots in the top and bottom plates are a plurality of bars 51 carrying on their upper ends above the top plate keys 52 marked to indicate the particular type form to which each key corresponds. While but two such keys are shown in the present instance, any desired number may be provided. The same mechanism being employed in conjunction with each key, the following description of one of 100 these mechanisms will be sufficient.

55 The key corresponding to the type form for printing the word "Cents" has its bar formed with a shoulder 53, Fig. 7, bearing against an angular end 54 of a bell crank 115 lever 55 rotatably supported on a spindle 56 mounted at its ends in the end walls of the housing described above. Lever 55 has an arm 57 the end of which is loosely engaged in a slot 58 in a bar 59 sliding longitudinally in bearing openings formed in the housing and casing walls as shown. The bar slides transversely toward and from the path of movement of the carrier yoke to position the end 60 of the bar for engagement with a lug 61 formed by the angularly turned end of the handle arm 26 of the yoke. This end of the bar is beveled on one side as shown for a purpose presently to be explained. A spring 62 coiled about a pin on 120 125

the housing is engaged as shown with a lug 63 of the bar to move the latter outwardly to inactive position. This spring thus tends to swing lever 55 and maintain key 52 in raised position. Depression of the key however slides the bar inwardly to position its end 60 to engage and positively stop the selective movement of the yoke with the latter in position for printing the word "Cents." This is the result when handle 27 is shifted toward the left in Figs. 1 and 7 as is usually the case when the word "Cents" is selected owing to the particular arrangement of the type forms. When the handle 5 is moved in the opposite direction however, the beveled shape of the stop bar causes it to be slid outwardly without stopping the selective movement, as is found desirable in the use of the machine.

20. A similar key and stop mechanism is provided in the present instance for selecting the word "Dollars," advantage being taken of this latter mechanism however for operating also a stop mechanism for selecting the 25 form for printing "No cents." For this purpose the stop bar 59 of the "Dollars" key is formed with a laterally projecting lug 64 for engagement with one end of a bail shaped member 65 pivotally supported 30 on spindle 56. A spring 66 coiled about the spindle and engaged at its ends with the lever 55 and with the bail normally maintains the latter in yieldable contact with the bar 59. The other end of the bail works 35 in a slot 67 in a stop bar 68 slidably supported as described in connection with the bar 59. The inner end of this bar however is beveled on the opposite sides as at 69 so that it serves when advanced to arrest movement of the yoke toward the right exclusively. The depression of the "Dollars" key 40 thus advances both its particular stop bar 59 and the bar 68 corresponds to the type form for printing "No cents."

45. The operation of the machine has been described above in connection with its construction so that but a brief summary is required. Handle 27 is moved up and down the dial to position its pointer 28 over the 50 type forms successively selected for printing, the handle being depressed between such selective movements to connect the printing couple with the motor to effect the printing operations. When it is desired to print either the word "Dollars" or "Cents," the corresponding key is depressed as the handle is moved toward it from the right. Depression of the key advances its stop bar 55 as described to form an abutment against 55 which the carrier mechanism may be rapidly moved and instantly stopped with this type form positioned for printing, thereby facilitating its selection by affording a more rapid and accurate method of manipulation 60 of the parts. These stop mechanisms are returned by their springs to active position whenever released and are of course ineffective during movement of the carrier toward the right. Depression of the "Dollars" key 52 serves also to set the stop bar corresponding to the type form "No cents." With this bar set the selecting mechanism may be shifted directly to position for printing the word "Dollars" as the "No cents" stop is ineffective in this direction of movement. After printing the word "Dollars" however, by holding this key depressed, the selecting mechanism may then be shifted in the opposite direction and positively stopped in position for printing "No cents" as frequently desirable in the use of the machine.

65. Auxiliary stop key means is shown in the present embodiment for certain of the type forms most frequently employed in writing monetary values. It is obvious however that such mechanism may be provided for others of the type forms as may be found desirable for increasing the efficiency of the machine.

I claim as my invention:

1. In a machine of the class described, the combination with a plurality of type forms and a platen having a relative movement to selectively position the individual forms and platen in printing relation, an indicating device, and manual means cooperating with said device for effecting said selective movement, of mechanism comprising a key and a pair of spaced stops adapted to be set thereby for positively locating said manual means with either or both successively of a pair of said forms in printing relation.
2. In a machine of the class described, the combination with a platen and a carrier shiftable to bring a plurality of type forms selectively into printing relation with said platen, manual means for shifting said carrier and a dial for indicating said movement, of auxiliary stop means comprising a yieldable sliding bar having an end beveled on one side for positively stopping said carrier in one direction of movement thereof only and a key for sliding said bar to active position.
3. In a machine of the class described, the combination with a platen and a carrier shiftable to bring a plurality of type forms selectively into printing relation with said platen, manual means for shifting said carrier and a dial for indicating said movement, of auxiliary stop means comprising a plurality of longitudinally slidably yieldable spaced bars each having an end beveled on one side and adapted to be positioned for positively stopping said carrier in one direction of movement thereof only with a corresponding one of said forms in printing relation and key operated means for selectively positioning said bars.
4. In a machine of the class described, the combination with a platen and a carrier

- shiftable to bring a plurality of type forms selectively into printing relation with said platen, manual means for shifting said carrier and a dial for indicating said movement, of a stop movable toward and from the path of movement of said carrier and having a beveled portion on one side thereof for engagement by the carrier during movement of the latter in one direction for displacing said stop, spring means normally retracting said stop, a key and a bell crank lever connecting said key and stop for advancing the latter to active position.
5. In a machine of the class described, the combination with a platen and a carrier shiftable to bring a plurality of type forms selectively into printing relation with said platen, manual means for shifting said carrier and a dial for indicating said movement, of spaced stops movable toward and from the path of movement of said carrier, said stops being beveled on opposite sides thereof, respectively, for displacement by
- 25 said carrier during movement of the latter in corresponding directions, spring means normally retracting said stops, and a key connected with said stops for advancing the same to active position.
6. In a machine of the class described, the combination with a platen and a carrier shiftable to bring a plurality of type forms selectively into printing relation with said platen, manual means for shifting said carrier and a dial for indicating said movement, of spaced stop bars slidable longitudinally toward and from the path of movement of said carrier, said bars being beveled on opposite sides thereof, respectively, for displacement by said carrier during movement of the latter in corresponding directions, spring means normally retracting said bars, a key, and means comprising a bell crank connecting said key and bars for advancing the latter to active position.

WALTER B. PAYNE.
